ABSTRACT

The invention is a method, and apparatus specifically designed to carry out the method, of lessening and substantially eliminating the sloshing and surging within bodies of confined liquid in transit as in a railway tank car.

**INHIBITION OF END-TO-END SLOSHING,
LONGITUDINAL OF THE DIRECTION OF
MOVEMENT, WITHIN CONFINED BODIES OF
LIQUID IN TRANSIT**

FIELD OF THE INVENTION

The invention pertains to stabilizing the surface level and to stabilizing the distribution of weight of liquid bodies in vessels in motion which are being subjected to inertial changes due to variations in speed and/or direction of movement. Serious damage has occurred and continues to occur involving one or more tank cars containing liquid, especially when not completely filled, including derailment or collision and concomitant disastrous happenings, as for example, spillage of a liquid chemical or fuel after derailment or collision. The causal relationship between the movement of liquid within a tank car and a train wreck had not heretofore been fully realized.

However, I have now ascertained that the shifting of weight of the liquid contents of a tank car, resulting from the surge of liquid to the front or rear thereof due to changes in momentum, e.g., that occurring in deceleration or acceleration, particularly when relatively abrupt as is often unavoidable in train movements (manifested by lurching and jolting), is often the direct cause of serious train accidents. This imbalance of weight has been observed sometimes to cause either the rear flanged trucks or more frequently the front flanged trucks of a tank car, occasioned by sudden changes in velocity, to rise clear of the rails. The intervention of any one of a number of forces prevents the flanged truck wheels on one or both sides of the car from properly and completely repositioning themselves simultaneously on the tracks, and a wreck of varying seriousness ensues. The sudden shifting of weight within the tank car directly causes these tragedies. Moreover, we have noted that train wrecks due to any cause wherein a partially loaded tank car was derailed, even though not shown to have caused the wreck, are often accompanied by disastrous fire damage due to spillage of the contents of a tank car containing a flammable liquid. Spillage in such instances resulted from the sudden tremendous force of the impounded liquid against the end of the tank car following derailment. Unfortunately, many of the most serious of such railway tragedies occur near population centers because trains normally decelerate and accelerate more frequently at or near such centers.

PRIOR ART

The primary cause of railway tank cars and tank auto truck upsets and spillage has not heretofore been fully recognized to have been due to the slug movement of the liquid in the moving tank. However, some splash plates have been known to have been employed for various purposes in liquid containers, as in: U. S. Pat. Nos. 1,616,008; 1,661,324; 1,832,632; 2,379,126; 3,144,953; 3,288,186; 3,310,070; and 3,615,999. The prior art, not having recognized the seriousness of the liquid weight shifting as a unitary body within a moving tank, accordingly directed its efforts toward the accomplishment of other objectives and failed to break up the unitary movement of the liquid as it sloshed from end to end. Furthermore, they were difficult to install and required soldering, welding, riveting to the tank interior, or the like and were insufficiently resilient or shock

absorbent to stifle adequately the liquid movement which sometimes acquires rhythm which builds up tremendous forces, especially in a series of tank cars containing liquid.

OBJECTIVE OF THE INVENTION

The primary objective of the invention, accordingly, is to inhibit surging and sloshing, and weight imbalance due thereto, in a confined body of liquid in motion.

SUMMARY OF THE INVENTION

The method of the invention comprises disrupting the unitary or end-to-end (slug) movement, due to deceleration or acceleration within a body of liquid being moved as a mass (as opposed to movement by flow as in a pipeline), at intervals throughout the body of liquid, provision being made thereby for the greater part of the shifted total weight due to such deceleration or acceleration to be temporarily restricted to fractions or portions of the body of liquid at each interval and the greater part of the total force of the movement within the liquid to be thus largely absorbed independently at the intervals and only ultimately at a reduced force, and extended over a period of time, to be received in a much diminished state against a resilient limiting surface adjacent to the surface that confines the body of liquid, located opposite to the direction of deceleration or acceleration. When a tank of liquid is decelerated, the swell of liquid tends to move forward and when accelerated, to move backward.

Otherwise stated, the method of the invention insures interruption of the continuous or slug movement of a unitary confined body of liquid by interrupting the slug movement at intervals throughout the liquid, the force of the liquid movement thereby being dissipated so as to greatly lessen the impact at the limit (e.g., end of a tank car) of the body of liquid.

The apparatus of the invention comprises a plurality of baffles in series positioned in a vessel to be (or being) moved, substantially transverse to the direction of movement of the vessel and supported and held in place by interbaffle bracing to constitute an integral structure terminating at the ends or sides of the vessel corresponding to the line of anticipated (or present) movement, in resilient shock-absorbing adjustable members in contact with said ends or sides of the vessel.

The various members of the entire assembly are best bolted together inside the vessel, but are not secured directly to the vessel itself. Both the method and apparatus of the invention have specific application to a railway tank car or automotive-mounted tank to prevent excessive sloshing and surging of liquid contents when the car is being moved and therefore to inhibit the likelihood of derailment and damage.

An optional feature of the apparatus is a pipe-nozzle arrangement for spray-cleaning of the car after the transported liquid has been removed. Such may consist of a pressure system having an inlet attachable to a source of organic solvent or water containing adequate and suitable cleansing agent, a main pipe with distribution branches and nozzles directable to the baffles and to the recesses of the various parts of the tank car whereby any remaining liquid or resulting solid can be readily flushed from the car through the conventional drain thereof. The pipe-nozzle arrangement is laid out

within the car employing the structure of the baffle system.

Any durable material of adequate strength and which is chemically unreactive with the contents of a tank car may be used in the construction of the apparatus. Iron and steel are not favored in some instances (unless properly coated) because of their corrosivity in an oxidative environment. Any of various resins (more commonly called plastics), aluminum, magnesium or the like are preferred. Aluminum plate supported by aluminum channel or tubular aluminum is particularly recommended for general use.

DESCRIPTION OF THE DRAWING

FIGS. 1 to 5, of which the amended drawing consists, illustrate the invention.

FIG. 1 depicts schematically a sectional view of the interior of a railway tank car or a tank for mounting on an automotive truck chassis. It is designed for use in a conventionally front-to-rear elongated and generally circular or oval-shaped cross-sectional tank equipped with conventional loading port 4 and closure or cover 6 therefor. It shows baffles 2 having a periphery corresponding more-or-less to the contour of the tank but of insufficiently tight fit to be entirely fluid-tight. In each baffle is man-hole 3, which is entirely optional, provided with cover 5, and tightening means (usually called a crowfoot) 8 which are usually not completely closed in use. The edges of the baffles usually rest on the tank bottom but do not form sealing engagement with the bottom, fitting relatively loosely with the sides and top. The baffles are usually conveniently made up of sections which are intended to permit the baffles to be taken into the tank unassembled and the sections bolted together inside of the tank. (For better concept of assembly, see FIG. 3).

Interbaffle braces 12 are shown diagonally bolted to the successive baffles to support and hold them in place, and yet allow some limited movement of the baffles under stress. The braces may be on any plane, e.g., horizontal, vertical, or any angle thereto. The baffles may, but need not be, equally spaced. However, there must be at least two baffles, one located some distance from each end of the tank to insure results and preferably more than two baffles in long tanks. The middle portion of the tank need have no baffle, although one or more are often helpful and therefore may be desired. The interbaffle braces will, of course, be of a length dependent on the spaces between baffles and the cross-sectional area of the tank. Spring assemblies 14 are positioned at opposite ends of the tank. They are each composed of plate 16, screw 18 centrally positioned in coil spring 20 which rests against 16, and cushioning ring 22, and jack or tightening nut 24 which may be extended into a wheel, bar, or handle to provide greater leverage for operation. Drainage vent and plug 25 are shown in the lower middle of the tank.

FIG. 2 is a view taken at 2 — 2 of FIG. 1. It shows reinforcing framework 10 bolted to baffle 2. It also shows manhole 3 which is of a size adequate for a man to pass through for making minor repairs and for the removal of sludge or residual solid material from the car. They may also be useful in the installation of the apparatus of the invention by providing for passage of personnel, parts, and tools when the apparatus is assembled in place, working from the ends toward the

center of the car where the car manhole is usually located.

FIG. 3 shows a modified baffle having segments 30 cut out to assure free leveling of the liquid in a tank, even following any sudden disturbance thereof. The same objective may be attained by any planned irregularity in the edge of the baffle or perforations therein. This baffle is shown, merely for purposes of illustration, to be composed of 12 sections 27 which can be assembled within the tank. FIG. 3 also shows wing nuts 28 as a convenient means of assembling and attaching the reinforcing frames to the baffle sections.

FIG. 4 shows a shock-absorbing spring assembly, for use at the car end, attached to the first next baffle from the car end. Spring 20 is of spring grade metal and is mounted on screw 18, one end of which presses against cushioning ring 22 which in turn is in forced contact with the inner surface of the end of the tank (not shown) and the other end of which presses against plate 16. FIG. 4 illustrates an embodiment of the invention wherein the spring assembly, bracing, and first baffle comprise a unit which is assembled and installed as such. The bracing 36 shown here is of spider leg design, there usually being from three to seven legs, commonly four equi-spaced such legs being used.

FIG. 5 is a side or elevational view of the entire apparatus of a further embodiment of the invention as it would appear when assembled and positioned in a railway tank car, the tank car itself not being shown. It also shows optional permanently fixed wash-down features 40 of the invention, whereby the baffle system serves to support it.

FIG. 6 is an embodiment of the invention which shows the application of a shock-absorbing concept wherein, instead of spring 20 shown in FIG. 4, a compressible or resilient rubber or plastic material 29 of a generally cylindrical or elliptical shape is employed.

EXAMPLE OF THE INVENTION

To illustrate the practice of the invention, 22,000 gallons of a flammable liquid, chemical, e.g., liquid butane, chlorine or the like, is to be shipped via a 55 feet long, 30,000 gallon capacity tank car. The tank car, prior to being loaded, is equipped in accordance with the invention. Pre-cut and pre-drilled sections of aluminum plating for baffles and reinforcing channels therefor, and interbaffle bracing channels, and member pieces of the end spring assemblies (with or without provision for man-hole, covers, and tensioning jack screws) and suitable nuts and bolts are passed in selected order down into the tank car. Installation proceeds toward the middle from each end of the car starting with the spring assemblies. During the installation, the springs are usually compressed so that the edges of the baffles are in only slight frictional contact with the bottom interior of the car for easy movement as necessary. The baffles are assembled in order from each end leaving the man-holes (if provided) until all else has been assembled. The springs in the spring assemblies at each end are then relaxed to some extent (i.e., the springs are elongated) causing the entire assembled structure, between the tensioning nuts of the spring assemblies, to draw toward the middle of the car, i.e., the assembled structure acquires between the tensioning nuts thereby a slightly less overall length of say between one and about 10 inches which simultaneously causes the interbaffle braces to press somewhat harder against

the baffles and hold them more firmly though continuing to rest on the bottom of the tank. Just enough compression of the springs is usually maintained to provide good firm contact with the ends of the tank. The spring assemblies allow for expansion and contraction of the structure in accordance with temperature changes. The man-hole covers (if man-holes were deemed desirable) are last of all put on and closed, although they may be left loose enough to aid in leveling of the liquid after a disturbance. No part of the equipment is secured, as by screws, bolts, welds or the like, to the car; there is only frictional contact.

Tank cars used today are larger than in former years. 48,000-gallon capacity, 78-foot length cars, are often employed and 30,000-gallon capacity, 55-foot length, are common whereas not long ago a 44-foot car was considered maximum. Such large volumes produce tremendous force when caused to slosh from end to end of a car and derailments due thereto are increasing. The ensuing damage by fire, chemical attack, noxious fumes, and the havoc wrought on track and equipment and nearby homes makes such tragedies into catastrophes.

The example hereinabove is for illustration only. The technique of installing the equipment of the invention to use in the method of the invention to prevent unbroken sloshing of the body of liquid over the entire length of the car may be that in accordance with the available facilities and the exigencies of the particular situation. Iron and steel may be used where there is no danger of chemical reaction therewith or from ignition from sparks or friction. Aluminum, magnesium, brass, bronze, or ignition of the available strong and durable plastics or resin is often preferred. The cushioning ring between the end of the car and the spring of the spring assembly is preferably of Teflon, nylon, polycarbonate, polyester, Kralac or other resin cured to a suitable hardness and tensile strength to provide desired wear and resiliency.

The method and apparatus of the invention are applicable to the movement of any confined body of liquid of appreciable volume as in railway tank cars and automotive truck-mounted tanks.

Having described my invention, what I claim and desire to protect by Letters Patent is:

1. The method of inhibiting the unitary end-to-end movement, within a confined body of liquid being transported due to deceleration or acceleration of the liquid being moved as a body which end-to-end movement, longitudinal of the direction of movement of the body of liquid, when unimpeded causes severe shifting of weight and a progressive force moving through the liquid in a forward direction when the body of liquid is decelerated and in a rearward direction when the body of liquid is accelerated, until stopped by the confining limit of the body of liquid, which comprises an integrated system consisting essentially of disrupting said forward or rearward movement at intervals throughout the body of liquid along the path of said movement within the body of liquid, providing for the greater part of the weight so shifted to be restricted at specific instances to limited portions of the body of liquid as defined by such intervals, and providing the greater part of the force of the movement within the liquid to be largely absorbed independently at such intervals, but to provide that a minor portion of an unusually large force

making impact at any such interval be dispersed or dissipated to other intervals and thereby dissipated over a relatively large volume, whereby a markedly lessened shifted weight and lessened force ultimately extend to the confining limit of the body of liquid.

2. The method according to claim 1 wherein the lessened force ultimately reaching the confining limits of the liquid is further diminished and rendered inconsequential by providing a resilient cushioning means at each limit which means cooperates with the interruption of the progressive force within the body of liquid in the path of movement.

3. The apparatus for inhibiting the end-to-end sloshing and surging parallel to direction of transit of a confined body of liquid in transit comprising a plurality of baffles in series positioned in a vessel adapted to transport liquids, substantially transverse to the intended direction of movement of the vessel when in transit, said baffles allowing constrained liquid flow; interbaffle bracing diagonally secured to the faces of the baffles and extending generally longitudinally within the vessel to provide mutual support among the baffles to constitute a continuous resilient integrated unit; a tensioning device between each end of the vessel in the line of intended general direction of the vessel and the nearest inwardly positioned baffle therefrom, said tensioning so positioned between said next nearest baffle and vessel end as to cushion and absorb forces created by movement within the confined body of liquid and which forces register successively but in diminished effect on the baffles.

4. The apparatus of claim 3 wherein said baffles are equipped with man-holes and closable covers therefor.

5. The apparatus of claim 3 wherein said baffles are composed of a plurality of plate sections which are readily assembled within said vessel.

6. The apparatus of claim 3 wherein said tensioning device consists essentially of a compressible coil spring mounted on a centrally located screw having its axis positioned longitudinally of the vessel so that the outer end of the spring is between a cushioning ring in forced contact with the vessel and the inward end is forced against a generally circular plate on said screw, which plate is firmly engaged with spider leg bracing, said spider legs diverging from such point of engagement to firm attachment with the nearest inward baffle.

7. The apparatus of claim 6 wherein the inward end of said coil spring is in direct contact with the nearest baffle.

8. The apparatus of claim 3 wherein said tensioning device is a compressible solid of rubber or plastic material positioned between the end or side of the vessel and the nearest baffle.

9. The apparatus of claim 3 wherein said vessel is a railway tank car.

10. The apparatus of claim 3 wherein a pressurized wash-down piping assembly is laid out within said vessel and so positioned therein as to be supported by and accessible to, the members of said apparatus and provided with wash liquid outlets directed toward said members thereby to provide convenient in-place wash-down of said members without need to remove or adjust them.
